UNITED STATES PATENT OFFICE

92,956

DESIGN FOR AN AUTO TRAILER COACH

Ephraim P. Golden, St. Petersburg, Fla.

Application May 1, 1934, Serial No. 51,611

Term of patent 14 years

To all whom it may concern:

Be it known, that I, EPHRAIM P. GOLDEN, a citizen of the United States, residing at St. Petersburg, in the county of Pinellas, and State of Florida, have invented a new, original, and ornamental Design for an Auto Trailer Coach as shown in the accompanying drawing and described in the following specification.

In the drawing:

Figure 1 is a perspective view illustrating in general the main body streamline of one side and rear end of my new auto trailer coach design, overhanging the sunken structure;

Figure 2 is a perspective view of my new design illustrating the front end and the opposite side thereof to that shown in Figure 1;

Figure 3 is a front elevation of the design; and Figure 4 is a top plan view thereof.

The trailer design is characterized by the main side portions thereof, having a slight bell-shaped flared skirting, overshadowing the setback drop floor.

I claim:

The ornamental design for an auto trailer coach as shown and described.

EPHRAIM P. GOLDEN.
